(57) **CLAIM**

We claim the ornamental design for an attachment for a cleaning apparatus, as shown and described.

DESCRIPTION

FIG. 1 is a perspective view of an attachment for a cleaning apparatus embodying the invention;

FIG. 2 is a right side view of the attachment for a cleaning apparatus of FIG. 1;

FIG. 3 is a left side view of the attachment for a cleaning apparatus of FIG. 1;

FIG. 4 is a front view of the attachment for a cleaning apparatus of FIG. 1;

FIG. 5 is a rear view of the attachment for a cleaning apparatus of FIG. 1;

FIG. 6 is a top view of the attachment for a cleaning apparatus of FIG. 1; and,

FIG. 7 is a bottom view of the attachment for a cleaning apparatus of FIG. 1.

The elements shown in broken lines are included for the purpose of illustrating environment and form no part of the claimed design.

1 Claim, 4 Drawing Sheets
